UNITED STATES PATENT OFFICE

2,452,982

SUBMERGED RECIPROCATING SCREEN

Byron M. Bird, Columbus, Ohio, assignor to The Jeffrey Company, a corporation of Ohio

Application June 25, 1945, Serial No. 601,397

1 Claim. (Cl. 209—269)

1

This invention relates to an improved method of and apparatus for submerged screening by which granular material is screened or separated according to size below a water or liquid level.

An object of the invention therefore is to provide an improved method of and apparatus for sizing material by a continuous operation which eliminates all dust hazard and which effects a very efficient separation of material into two size ranges.

Another object of the invention is to provide improved apparatus for the submerged screening of fine material from a mixture of various sized particles thereof wherein the fine particles to be screened are of such character as to permit them to become at least partially suspended in a liquid medium, the apparatus suspending said particles in a liquid and injecting or spraying liquid into that in which the particles are suspended to precipitate or settle the suspended particles therefrom, the apparatus causing the precipitated or settled particles to pass through a screen into a collecting chamber.

Another object of the invention is to provide an improved method and apparatus of the above mentioned type in which a counter-flow preferably pulsating water or other liquid is employed to increase the efficiency of the screening operation.

A further object of the invention is to provide a dustless method of separating material and particularly granular material by a screened action.

Other objects of the invention will appear hereinafter, the novel features and combinations being set forth in the appended claim.

In the accompanying drawings,

Fig. 1 is a combination elevational and sectional view showing apparatus involving my invention;

Fig. 2 is a sectional view taken on the line 2—2 of Fig. 1, looking in the direction of the arrows;

Fig. 3 is an enlarged sectional view taken on the line 3—3 of Fig. 1; and

Fig. 4 is a plan view of a portion of the apparatus showing a particular detail.

In the drawings there is illustrated a preferred embodiment of the apparatus involving my invention which is one form of apparatus capable of carrying out the invention of my improved method.

Said apparatus includes a container or tank 10 provided with a plurality of cells, sections or compartments 11 and 12, respectively. As here-

2

inafter described more completely, section or compartment 11 is the oversize or large particle section or compartment and it receives the large or oversize material which settles to its conical bottom 5: where it may be flushed out by opening a control valve 13. A similar control valve 14 is provided for the generally conical bottom of section or compartment 12 to flush out the undersize or small size particles which accumulate therein.

10 The cell section or compartment 12 receives the downwardly extending screening deck 15 of a vibratory electro-magnetic screen 16 having a vibratory electro-magnetic motor 17. The electro-magnetic vibratory screen 16 may be generally 15 of the structure disclosed in the patent to James A. Flint, No. 2,153,243, except that the deck 15 is of different construction and there is not necessarily any adjustment between the deck and the motor armature. This type of vibratory screen, 20 per se, is well known in the art and it operates at a frequency of 3600 vibrations or cycles per minute when energized from a mixed current source, the alternating current of which has a 60 cycle frequency. In known push-pull types 25 of vibratory screens of this same general character the frequency for 60 cycle alternating current will be 1800 vibrations per minute.

The screen 16 is suspended from any desired superstructure by means of non-shock transmitting hangers 18, there being at least three and preferably four of said hangers, two attached to the motor 17 and two to the deck 15, as clearly illustrated in the drawings.

While I prefer to employ an electro-magnetic 35 screen of the above mentioned type, it is evident that within the scope of my invention, particularly in some of its broader aspects, a mechanical or other type of screen may be employed. The screen illustrated, however, is particularly adapted 40 for my invention because of the fact that the motor 17 is above the deck 15 and thus there is no problem of suspending the screen with the screen cloth below the water, as hereinafter described.

45 The screening deck 15 extends in part below the liquid level 19 of the water or liquid in the section or compartment 12, which liquid level is determined by an outlet means in the form of an overflow weir 20 leading to an overflow chute 21 adjacent the rear or right-hand end of the tank 10.

The screening deck 15 is, of course, rigidly attached to the armature of the motor 17 to receive vibratory motion developed thereby and 55 it includes a pair of spaced water tight side walls

22 which are adequately reinforced by cross members 23 clearly illustrated in Fig. 1 of the drawings. Across its rear and extending between the side walls 22, the deck 15 includes an end plate or wall 24 which makes the end of the deck 15 also watertight.

At its front the upstanding front edges of the side walls 22 of deck 15 are connected to the adjacent side walls of the tank 10 and to a transversely extending partition member 25, which is a portion of a partition designated generally 26 which separates the sections or compartments 11 and 12, by virtue of a U-shaped flexible water proof partition or wall member 27. The flexible partition member 27 has its outer edges connected by water tight connections with the side walls of tank 10, as clearly illustrated in Fig. 3 of the drawings. The bottom edge of the flexible partition member 27 is similarly attached to the partition member 25. In addition, the inner edges of the flexible partition member 27 are connected by water tight connections, with the front of the side walls 22 of the deck 15 and with a transverse plate 28 (see particularly Fig. 1) forming the bottom front portion of said deck 15.

The complete partition 26 also includes a center upright partition plate 29, the side edges of which are connected by spaced flexible water proof partition members 30 to the adjacent side walls 22 of the deck 15, as best illustrated in Figs. 2 and 3 of the drawings. The plate 29 does not vibrate with the deck 15 since it is not rigidly attached thereto, but it is supported by adjusting levers 31 which are pivoted to a crosspiece 32 forming a part of the tank 10, the levers 31 being adjustable through a limited degree by an adjusting hook 33 which co-operates therewith and which is adjustably mounted on an angle member formed at the front end of the tank 10, as clearly illustrated in Fig. 1 of the drawings.

The flexible partition members 30 provide for limited up and down adjustment of the plate 29. This provides for adjustment of the size of an opening or orifice 34 which is formed between the bottom edge of the plate 29 and a screen cloth holding roll 35 at the discharge or lower end of the deck 15.

Near the bottom of the deck 15 there is the usual screen cloth 36 which extends the full length of the deck 15 and is supported on spaced transverse supporting and arching members 37 extending to a tension adjusting head roll 38 at the upper right-hand end of the screen cloth 36 which has a close fit with the bottom of the deck end plate 24. A screen cloth adjusting member 39 is provided for adjusting the tension of the screen cloth 36.

The granular material which is to be separated is preferably relatively fine particle or at least contains a relatively fine constituent and this submerged screening is particularly effective in separating very fine particles of material from a mixture which includes them. To provide proper feeding of the material to be separated or classified, I provide a feed chute 40 which may be of any desired form; for example, it may be a chute of a vibratory feeder. This feed chute is preferably closed at its discharge end and extends below the water level 19, discharging the material adjacent the upper or feed end of the screen cloth 36.

I have also found that with many materials it is desirable to spray them with water and to this end I have provided a pair of sprays 41 which

spray the material while in the chute 40, thus delivering the material with an appreciable water content to the screen cloth 36. In some instances this spraying is not necessary.

5 The principal amount or all of the water delivered to the tank 10 is preferably fed by way of water pipe or fluid inlet means 42 under the control of valve 43 which delivers the water to the large particle compartment 11 in which the water level, indicated at 44, will be slightly above the water level in the fine compartment 12.

As a consequence of this fact, which is quite important in many instances, the water reaching the fine compartment 12 must flow through the opening or orifice 34 from compartment 11 to compartment 12. It is, of course, obvious that in operation the large size material must also flow through this orifice or opening 34 and consequently there will be a counter-flow of water against this oversize material. This counter-flow of water will wash the material free of any small particles and thus assure an efficient separation of the material into sized constituents.

20 As best illustrated in Figs. 1 and 4 of the drawings, I also preferably provide one or more stationary partitions which extend downwardly between the side walls of the deck 15 and divide the fluid compartment thereof into a plurality of successive screening sections, compartments or cells. 25 As best seen in Fig. 1 of the drawings, there are two such partitions 45 and 46. These partitions are of similar construction, but partition 45 is necessarily higher than partition 46. Said partition 45 is supported on a transversely extending combination support and spray or jet pipe 47 which in turn is supported at each end by a pair of upstanding angle members 48 which are rigidly attached to the two side walls of compartment 12, as clearly illustrated in Figs. 1 and 4 of the drawings.

20 The partition plate 45 hangs downwardly from the pipe 47 to which it is rigidly attached by welding, bolts or any other desired means. Said plate 45 preferably has its side edges bent inwardly, as clearly illustrated at 49 in Fig. 4 of the drawings, to provide a wiping contact with the adjacent side wall 22 of the deck 15. If desired, the plate 45 may be connected to the side wall 22 by a flexible partition member, the connection being effected substantially as provided between the plate 29 and the side wall 22 by the flexible member 30, as illustrated in Figs. 2 and 3 of the drawings. Conversely, plate 29 may have a sliding connection with the side wall 22 of the type illustrated at 49 for plate 45.

60 Adjacent its bottom the plate 45 preferably carries a flexible rubber or canvas strip 50 which provides a flexible seal with the screen cloth 36. This strip 50 has sufficient flexibility that oversize material can travel under it and reversely flowing fluid can likewise travel under it. The construction of the partition plate 46 and its associated mechanism is similar to that described in connection with plate 45. Water is supplied 65 to the pipe 47 and a similar pipe associated with partition 46, preferably under the control of valve means, that for pipe 47 being seen at 51 in Fig. 4.

65 As a consequence of these partitions 45 and 46 and their associated structure the compartment provided by the deck 15 is divided into a plurality of successive screening compartments, sections or cells and this helps in the settling of particles, particularly if they are of very small size. Furthermore, the individual water supply

ing pipes, such as pipe 41, provide for an adjustment of the amount of water to be supplied to each screening compartment and consequently an adjustment of the quantity of water flowing downwardly therethrough because this water is delivered to the top of the liquid or pulp in each compartment and it will tend to flow downwardly through the screen cloth 36 or under the strip 50 by reason of the super-elevation of the water level in the compartment. Because of this flow and because the water is introduced into the compartment in the form of spray or jets the water will aid materially in settling or precipitating the fine particles of material which may tend to form a colloidal solution, suspension or pulp in said cell. Furthermore, the cell-like construction of the screening deck 15 prevents suspended fine particles from floating in the liquid from the feed side which is the right-hand side, as viewed in Fig. 1, to the discharge or left-hand side of the deck 15 and there settling and being discharged with oversize material into the section or compartment 11. Obviously, the partitions 45 and 46 will prevent such a flow of fine particles and cause them to settle on the screen cloth 36 which they will ultimately pass through.

It is, of course, to be understood, however, that in some of its broader aspects these partitions 45 and 46 may be omitted, though in a more complete aspect of the invention they are highly desirable and important.

As illustrated in the drawings, the screen cloth 36 has a slope from the feed end to the discharge end and this slope is preferably from 20 degrees to 30 degrees, depending upon the material being treated and the size ranges of the material.

The operation of the apparatus, with the consequent carrying out of the invention of my method, is as follows. The vibratory screen 16 is energized and the deck 15 will be placed in vibration, thus, of course, causing vibration of the sloping bottom screen cloth 36. The electro-magnetic motor 17 imparts a reciprocatory rectilinear or push-pull motion along an axis which passes longitudinally through it and through the screen bottom 36 of the deck 15 at an acute angle. Because the axis of the reciprocatory motion of the electro-magnetic motor 17 is positioned to intersect the sloping bottom screen 36 at an acute vertical angle the rectilinear vibratory motion of the motor 17 causes the screen to impart to material upon it a distinct vertical or upward motion component which is essentially a screening component and a distinct horizontal motion component which is essentially a conveying component. The screen cloth 36 is preferably entirely below the liquid level 19 for it has been found that under certain circumstances if a portion of it projects above the liquid level the screen cloth will be broken in a very short time by the vibration.

The material to be separated into two size ranges is delivered by the feed chute 40, either with or without being wetted by the addition of water from sprays 41, to the upper end of the screen cloth 36 and preferably substantially over its entire width. The granular material being separated will, of course, flow downwardly over the screen cloth 36 and be separated, with the fine particles passing through the screen and into the bottom of section or compartment 12, including those particles which are fine enough to pass through the mesh of the screen cloth 36 which preferably is 10 mesh or less. The larger particles will ultimately flow over the lower edge

of the screen cloth 36 and through the opening or orifice 34, falling through the water to the bottom of the section or compartment 11. The accumulated material in the bottoms of the sections or compartments 11 and 12 may be periodically flushed out by opening their respective control valves 13 and 14.

It will be seen that material passing over the deck will be positively elevated within the water or liquid above the screen by the vertical motion component and that the material will be positively conveyed over the screen by the horizontal motion component. The upward stroke of the screen acts in opposition to the mass of the fine particles of material which are adjacent its upper surface and in opposition to the inertia of those fine particles of material which are falling against its upper surface, therefore the upward stroke of the deck co-operates to force the fine particles of material through the screen 36. The particles of fine material, after having passed through the screen 36, settle in the section or compartment 12.

The principal part or all of the water involved will be delivered by pipe or fluid inlet 42 under the control of valve 43, first to compartment 11 from which it will flow through the opening or orifice 34 counter to the flow of oversize material therethrough. This is the only opening by which the water can flow from cell section, or compartment 11 into cell section, or compartment 12. The water in section, or compartment 12 which comes through the orifice 34 can only flow out of section or compartment 12 over weir or outlet 20 by way of chute 21 by flowing through the screen cloth 36 because the side walls of the deck 15 are attached to the partition 26 and extend above the level of the water in section 12. Thus the walls of the deck and the partition 26 co-operate to form a means which provides a fluid tight container structure or compartment, except for opening or orifice 34 and the sloping screening bottom 36. This means or structure insures that all of the water and fine particles of material entering section or compartment 12 must pass downwardly through the sloping screen bottom 36.

The water flowing through the screen cloth 36 will, of course, aid in carrying or forcing the fine particles therethrough into section or compartment 12, which particles will settle out in the bottom thereof while the water, free of the granular particles, will flow or be decanted from section or compartment 12 over the weir or fluid outlet 20 as above mentioned. It has been found in practice that this is a very desirable method of continuously separating granular material into constituents of two size ranges and is particularly desirable where dust is a hazard or otherwise undesirable and in which fine particles are to be separated to maintain the level of the water in section or compartment 12 above the bottom of the screen deck and below the top of its sides.

It is again particularly pointed out that the axis of vibration of the deck 15 makes an acute angle with the plane of the screen cloth 36 whereby the vibratory motion of the screen cloth imparts vertical and horizontal motion components to material upon it and that these components are such as to give a positive conveying and elevating action to the material. As a consequence, it is not entirely necessary that the screen cloth 36 be sloping downwardly as illustrated. This is important because in some instances a

much deeper tank, longer deck, and thus more complex structure would be required if gravity alone were to be relied upon to effect a movement of the material from one end of the screen cloth 36 to the other.

It may further be pointed out that the spaced partition members, due to their flexible construction, provide for limited adjustment of the partition plate 29 and thus provide for adjustment of the size of the opening or orifice 34.

It is also to be noted that the partitions 45 and 46 do not vibrate with the deck 15 and that because of this fact the openings or passageways between the flexible strips 50 and screen 36 through which material must pass to enter the successive screening compartments are not of a constant size, that is, the area of the openings will vary as the deck vibrates. This is also true of the adjustable opening or orifice 34. As a result of this variation in size of the orifice 34 and the passageways between the cells of the deck 15, water or liquid flowing therethrough counter-current to the flow of material tends to flow with a pulsating action. This action is important in aiding in the separation of the fine particles of material from the coarse materials in the areas adjacent the orifice 34 and the passageways 35.

Obviously those skilled in the art may make various changes in the details and arrangement of parts without departing from the spirit and scope of the invention as defined by the claim hereto appended, and I therefore wish not to be restricted to the precise construction herein disclosed.

Having thus described and shown an embodiment of my invention, what I desire to secure by Letters Patent of the United States is:

Material screening apparatus of the submerged in fluid medium type adapted to screen fine particles of material from a mixture of various sizes of particles of material wherein the fine particles to be screened are of such character as to permit them to become at least partially suspended in a fluid medium, said screening apparatus including a fluid container having partition means including an opening therein dividing said container into sections, one for receiving screened fine particles and one for receiving oversize particles of material, a screen in said fine particle receiving section having closed sides flexibly connected to said dividing partition about the opening therein and extending upwardly therefrom, a plurality of partitions depending to said screen crosswise thereof dividing said screen into compartments said partitions having flexible bottom

edges positioned adjacent to said screen, fluid inlet means for supplying fluid to said oversize particle section, overflow fluid outlet means associated with said fine particle section, said overflow fluid outlet means being positioned to determine the level of the fluid above the screen in the fine particle section of said container, means for depositing material to be screened in the uppermost compartment of said screen, means for wetting the material prior to its being deposited therein, jet means adapted to inject fluid into the fluid above said screen and adjacent the partitions therein to cause precipitation of fine particles of material in said fluid and to cause a flow of fluid through said screen into said fine particle section of said container thereby carrying precipitated fine particles of material therewith, and motor means for imparting vibratory motion to said screen at an acute angle with respect thereto, said screen thereby imparting conveying motion components to material thereon and conveying material from one particle section to the next particle section beyond said flexible means on the dividing partitions, the fluid entering said oversize particle container section flowing through said opening in the container dividing partition into said fine particle section counter-current to the flow of oversize particles passing through said opening thereby washing the fine from said oversize particles, and said fluid then flowing from said fine particle section through said screen thereby tending to carry fine particles of material present from the fine particle section to and through the screen and thence into said fine particle receiving section of the fine particle section.

BYRON M. BIRD.
